DESIGN FOR A COOKING VESSEL

William A. Burnette, Hartford, Mich., assignor to
Burnette Castings Company, Hartford, Mich.

Application December 1, 1944, Serial No. 116,653

Term of patent 14 years

(Cl. D44—1)

To all whom it may concern:

Be it known that I, William A. Burnette, a citizen of the United States, residing at Hartford, in the county of Van Buren, State of Michigan, have invented a new, original, and ornamental Design for Cooking Vessels, of which the following is a specification, reference being had to the accompanying drawing forming part thereof.

The figure is a perspective view of a cooking vessel, showing my new design.

I claim:

The ornamental design for a cooking vessel, as shown.

WILLIAM A. BURNETTE.
